Fig. 17.

A technical line drawing of a cylindrical component, likely a piston or cylinder. The central vertical axis is labeled with the number 26. At the top, there is a circular opening with a diameter labeled 21. The top surface is marked with the numbers 32 and 60. The side of the cylinder features several circular features: two pairs of concentric circles labeled 63 and 64, and two pairs of smaller circles labeled 61. The lower portion of the cylinder is labeled with the number 58. A horizontal line, labeled 19, intersects the cylinder. At the very bottom, there is a flared base labeled 26. The drawing uses hatching to indicate different parts and a wavy line to represent a boundary.

UNITED STATES PATENT OFFICE.

DANIEL J. MURNANE, OF CHICAGO HEIGHTS, ILLINOIS.

FRAME STRUCTURE.

1,376,895.

Specification of Letters Patent.

Patented May 3, 1921.

Application filed November 27, 1918. Serial No. 264,313.

To all whom it may concern:

Be it known that I, DANIEL J. MURNANE, a citizen of the United States, residing at Chicago Heights, in the county of Cook and State of Illinois, have invented a new and useful Improvement in Frame Structures, of which the following is a specification.

My invention relates more particularly to improvements in frame structures requiring the properties of great rigidity and strength with minimum weight, an instance of such a frame structure being the frames used in aeroplane construction, as, for example, the frames of elevators and rudders, my invention having been devised, more particularly, for embodiment in frames of this general character.

My primary object is to produce in a highly economical manner, frames possessing great rigidity and strength of highly stable character with the minimum of material, and without requiring welding at the joints between frame-members.

Referring to the accompanying drawings, wherein I have chosen to illustrate my invention as embodied in an aeroplane elevator—

Figure 1 is a face view of the frame of the elevator; Figs. 2, 3 and 4 are enlarged sections taken at the lines 2—2, 3—3, and 4—4 on Fig. 1, and viewed in the direction of the respective arrows; Fig. 5 is a side view of the construction shown in Fig. 4; Fig. 6 is an enlarged view in side elevation of one of the corners of the frame; Fig. 7 is a section taken at the line 7—7 on Fig. 6 and viewed in the direction of the arrows; Fig. 8 is a section taken at the line 8—8 on Fig. 6, and viewed in the direction of the arrows; Fig. 9 is a broken view in side elevation of the joint between one of the main members of the frame and a cross-member thereof; Fig. 10 is a section taken at the line 10 on Fig. 9 and viewed in the direction of the arrow; Fig. 11 is a section taken at the line 11—11 on Fig. 9, and viewed in the direction of the arrows; Fig. 12 is a view in elevation of the joint between certain intersecting cross-members; Fig. 13 is a section taken at the line 13—13 on Fig. 12 and viewed in the direction of the arrows; Fig. 14 is a section taken at the line 14 on Fig. 12 and viewed in the direction of the arrow; Fig.

15 is a view in side elevation of one of the main members of the frame and one of the similar hinge members connected therewith; Fig. 16 is a section taken at the line 16—16 on Fig. 15, and viewed in the direction of the arrows; Fig. 17 is a view in side elevation of one of the main frame members and a cross-member of the frame, together with the parts to which the elevator-operating devices are attached; Fig. 18 is a sectional view taken at right-angles to the view in Fig. 17, with certain parts shown in section and others in elevation; Fig. 19 is a section taken at the line 19—19 on Fig. 18, and viewed in the direction of the arrows; Fig. 20 is a section taken at the irregular line 20—20 on Fig. 17, and viewed in the direction of the arrows; and Fig. 21, a view like Fig. 2 showing a modification.

Referring to Fig. 1, the frame structure therein shown comprises, generally stated, the main tubular members 21 and 22, the member 21 being straight and the member 22 of general U-shape, affording the two side sections 23 and 24 and a connecting section 25, the side sections 23 and 24 being connected at their ends with the frame member 21; and cross-members 26, 27, 28, 29, 30 and 31, it being understood that the particular number of cross-members and their arrangement as shown is not necessary in the carrying out of my invention.

The frame member 21, which is hollow and preferably of general circular shape in cross-section, is formed of the body-portion 32 (Fig. 10) with webs, or flanges 33, extending in parallel relation lengthwise along the body-member 32, this member, with its flanges 33, being preferably formed from a single sheet of metal, as, for example, steel. In the manufacture of the member 21 the flanged portion 33 is preferably made of such a depth throughout the length of the member that the desired rigid connection of the adjacent marginal frame member and the cross-members therewith may be provided as hereinafter described, and between these various joints the flanged portion 33 is cut away or reduced to leave the flange of such depth only that these flanges may be secured together at intervals to the desired degree in any suitable manner, as by spot-welding, as indicated at 34, the idea

being to make this member 21 as light as possible, and still cause it to present the desired strength.

The member 23 is formed in the same way as the frame-member 21, its hollow body-portion, represented at 35, being preferably elongated in cross-section when used in the particular construction shown, as represented at Fig. 8, rather than circular, and in order that this frame member may be bent into the desired shape, as, for example, the general U-shape represented in Fig. 1, the flanges of the member 22 and corresponding with the flanges 33 of the member 21 are entirely cut away, except at the joints between the member 22 and the frame member 21 and cross-members 26, 28, 29, 30 and 31, and the portions, represented at 36, at which these flanges are secured together in any suitable way, as by spot-welding. If desired, the opposed edges of the metal at the points where the flanges 36 are entirely omitted may be brazed or welded together, and if desired the flange-ports 36 may be omitted and the securing between the remaining portions of the flanges of the member 22 be by brazing or welding the opposed edges of the body-portion 32 as stated. The formation of the frame-member 22, as explained, permits of it being readily bent into the general U-shape illustrated, or into any other desired form.

The connection of the ends of the frame member 22 with the frame member 21 is by means of the joints represented at 37 and 38, these joints being constructed in the same way, and therefore a detailed illustration of but one of the joints, namely the joint 37, is presented, this joint being shown in Figs. 6, 7 and 8, and of which the following is a description: In forming the member 23 the flanged portion 36 thereof at the upper end of this member is of full depth, this flange extending to the dotted line 38 in Fig. 6, and the hollow portion 35 of this member is flattened, these portions of the member 23 being telescoped with the adjacent end of the member 21, which is so formed that its flanges 33 at the extremity thereof are relatively deep, as represented, and the end of this member 21 is drawn down to closely fit against the flattened end of the hollow portion 35 which it straddles, as shown, rivets, or other fastening means, represented at 40, passing through these overlapping parts and firmly holding them in position, one of these rivets passing through the overlapping flanges 33 and 36.

The several joints between the cross-members of the frame and the marginal frame members are of substantially the same construction, and therefore a description of one of these joints will suffice, the joint between the cross-member 29 and the main frame member 21 being chosen for illustration, and

shown in Figs. 9, 10 and 11. In accordance with this feature of my invention, the flanges 33 at the point where the cross-member 29 is to be connected with the member 21, are left relatively deep, as shown in Fig. 10, in the forming of the frame member 21, and the upper end of the cross-member 29 is partially flattened and slotted at opposite ends, as represented at 29^a, in order that it may snugly fit over the flanges 33 at this point, preferably with a strap member 41, substantially of the same width as the partially flattened end of the member 29 at its widest dimension, interposed between the flanges 33 and the member 29, to avoid the flattening of the upper end of the member 29 to such a degree that it will impair its strength. The parts of the joint bearing the relations just explained are secured together in any desirable way, as through the medium of rivets represented at 100 passing through these overlapped parts, the upper extremity of the cross-member 29 at opposite sides of the flanges 33 preferably bearing endwise against the body 32 of the member 21. While the joints between the cross-members and the frame-member 21 involve the slotting of the cross-members as stated, such slotting of the cross-members where they connect with the frame-member 22 is omitted in view of the elimination of the flanges 36 at opposite sides of the joints.

The intersecting bars 27, 28 and 29 are connected together by means also forming a feature of my invention, a description of these means being as follows: In the particular arrangement shown, the cross-bar 29 is continuous, extending from the frame-member 21 to the frame-section 25, and the bars 27 and 28 extend from the cross-bar 26 and frame-section 23, respectively, to the bar 29, to which latter they are rigidly connected by the joint to be described. The ends of the bars 27 and 28 adjacent the bar 29 are preferably cut away to conformingly fit the sides of the bar 29, against which they abut, as shown in Fig. 12, and applied to these bars thus arranged in intersecting relation, are plates 42 which are of the same construction, but provided as rights and lefts, and applied to the intersecting bars from opposite sides thereof, as represented in Fig. 13. These plates are so constructed that they conformingly fit about the hollow bars which they oppose, and at the angles provided between these bars are inwardly offset, as represented at 43, to cause these plates at these portions to extend closely adjacent to each other, but so proportioned with relation to the cross-bars that in securing these plates to the latter, as by rivets represented at 44, or any other suitable means, these plates in being drawn together toward each other at these inset portions, will firmly grip, and become clamped

against, the surfaces of the cross-bars which they oppose, thus holding the cross-bars with a vise-like grip. To avoid any possible play between the bars and clamping plates, 1 employ metal locks shown as provided between the plates 42 and the bars 27, 28 and 29. These metal locks are provided by depressing the metal of the bars 27, 28 and 29, as represented at 45, and providing apertures 46 in these plates in registration with the openings 45, and after securing the plates and bars together as stated, any suitable metal, such as Babbitt metal, is poured through the openings 46 into the spaces provided by the depressed portions 45, thus forming the metal locks 47, which enhances the anchoring effect.

As is well understood in the art, an aeroplane elevator is mounted to have pivotal movement as through the medium of pivots or hinges. In the particular construction illustrated, provision is made for this by providing on the frame-member 21, at intervals along the latter, journal-heads 48. The construction of these journal-heads is the same, one of them being shown in detail in Figs. 15 and 16. The head comprises a body-portion 49 provided with an upwardly extending journaling section 50 of any suitable construction, and adapted to receive the pivot or hinge-rod not shown, this particular portion also having depending flanges 51. The body-portion 49 conformingly fits the body 32 of the frame-member 21, and at its flanges 51 embraces the flanged portion 33 of the member 21, these parts being rigidly connected together in the relation stated, as through the medium of rivets, or any other suitable means, represented at 51^a, the parts being preferably so proportioned that in the fastening operation stated the journal-heads 48 will be caused to very firmly and forcibly contact with the frame-member 21.

The same general form of joint as that shown in Figs. 12, 13 and 14 is employed at the juncture of the bar 27 with the bar 26. In this case, however, instead of providing two separate plates 42, a single plate, illustrated at 53, is provided, this plate presenting a body-portion 54 of general circular shape in cross-section, which embraces the bar 26, being preferably locked thereto by the metal locks 55 like the metal locks 47, and conformingly fitting at its opposed plate-sections about the adjacent end of the cross-bar 27, with these plate-sections between which the cross-bar 27 is confined, inwardly inset at the portions 56, as explained of the inset portions 43 of Fig. 12, at which 60 inset portions these plate-sections are rigidly secured together, as by the rivets represented at 57.

In the particular construction illustrated, the cross-bar 26 is equipped with laterally extending sections, in the form of arms or

brackets, for connection with the mechanism for tilting the elevator in either direction upon its pivotal support. These arms or brackets are shown as provided on the upper end of the cross-bar 26, and their connection with this bar, according to the preferred illustrated embodiment, is as follows:

The upper end of the bar 26 is connected with the frame-member 21 in the manner described of the connection of the bar 29 with the member 21, and as illustrated in Fig. 18. The bracket-sections referred to and represented at 58, these sections extending in opposite directions, are formed from a single sheet of metal having a deflected intermediate portion 59, which conformingly and closely fits against the hollow cross-member 26, as shown in Fig. 19, thus embracing it. At intervals along the brackets 58, as shown at the top and close to the bottom of these brackets, the brackets carry clips 60 and 61 which at their deflected sections 62 conformingly fit against the opposite side of the cross-bar 26, these clips being rigidly secured at their marginal portions 63 to the arms 58, as through the medium of rivets 64, these parts being so constructed that in the securing of the arms 58 and clips 60 and 61 together, these parts will be drawn into rigid engagement with the cross-bar 26, to produce a rigid structure. The upper portion of the bracket members 58 and the clip 60 preferably are shaped to conformingly fit the underside of the body-member 32 of the frame-member 21, as shown in Fig. 18, and the lower end of the portion 59 preferably abuts against the upper portion of the member 53 to augment the rigidity of the structure. To reduce weight the metal of the portion 59 and the part 53 is cut away at 59^a and 53^a, respectively. As a variation from the described method of forming the frame members, it may be stated that if desired instead of forming these members from sheets of metal, they may be formed from tubes drawn down to present the desired tubular body-section with lengthwise-extending flanges, the cross-sectional view of such member so formed being shown in Fig. 21.

From the foregoing description it will be understood that by constructing the marginal frame members as explained, and connecting the cross-members thereto as described, a very rigid and substantial frame of a very durable character and of relatively light weight may be very economically produced. Furthermore, the various joints illustrated and described are highly effective in producing a rigid structure capable of withstanding great strains, with high economy of material and at low cost, and while various features of my invention are illustrated and described in connection with an aeroplane frame structure, it will be read-

ily understood that they may be incorporated in structures for other purposes without departing from the spirit of the invention.

5. What I claim as new, and desire to secure by Letters Patent, is:

1. A frame-structure formed of marginal frame-members comprising hollow portions, each with a pair of flanges integral therewith, said flanges opposing each other and extending lengthwise of said hollow portions carrying them, and cross-members straddling said flanges and in such condition connected therewith.

15. 2. A frame-structure formed of marginal frame members comprising hollow portions with flange-sections extending lengthwise of the same, and cross-members straddling said flange-sections and in such condition connected therewith, said flange-sections being relatively deep at the points of juncture with said cross-members, and said flange-sections being fastened together at other points to render the frame members rigid.

20. 3. A frame-structure formed of marginal frame members comprising hollow portions with flange-sections extending lengthwise along the same and fitting flatwise together, and cross-members straddling said flange-sections and in such condition connected therewith, said flange-sections being relatively deep at the points of juncture with said cross-members and fastened together at other points to render the frame members

35. rigid.

4. A joint comprising two hollow members extending in an angular relation to each other and having hollow portions and flange-sections extending lengthwise thereof and beyond ends of said hollow portions, said flange-sections being arranged in overlapped relation with the flange-sections of one of said members located between the flange-sections of the other of said members,

40. 45 and means securing said members together.

5. A joint comprising two hollow members extending in an angular relation to each other and having hollow body-portions and flange-sections extending lengthwise thereof, the ends of said body-portions being flattened, and said flange-sections extending beyond the unflattened ends of said hollow portions, said flange-sections and said flattened portions being arranged in overlapped relation, with the flange-section and the flattened body-portion of one of said members located between the flange-section and the flattened portion of the other of said members, and means securing said members

60. 65 together.

6. A joint comprising two hollow members extending in an angular relation to each other and having hollow body-portions and flange-sections extending lengthwise thereof, the ends of said body-portions being

flattened, and said flange-sections extending beyond the unflattened ends of said hollow portions, said flange-sections and said flattened portions being arranged in overlapped relation, with the flange-section and the flattened body-portion of one of said members located between the flange-section and the flattened portion of the other of said members, and means extending through the flattened portions of said body-portions and through said flange-sections thereof for securing said members together.

7. A joint comprising a member formed of a hollow portion having flange-sections extending lengthwise thereof, said flange-sections being relatively deep at a portion thereof, a cross-member having a socket-forming end slotted at opposite sides thereof, said socket-forming end surrounding the relatively deep portion of said flange-sections and straddling the portion of the latter closely adjacent said hollow portion, and means extending through said cross-member and flange-sections for holding said members together.

8. A joint comprising members extending in an angular relation to each other, and securing means therefor formed of plate-sections secured to extend at opposite sides of said members and conformingly fitting against the latter with the metal of said securing means extending into the angles between said members, certain of said members containing depressions in their surfaces with an opening in said plate-sections registering with each of said depressions and with metal cast in said depressions through said openings.

9. A metal lock for overlapping members, comprising a body of metal cast through an opening in one of said members into a depression in the other of said members and extending into said depression and opening, the cross-sectional area of said depression being greater than that of said opening.

10. In a frame-structure, the combination of a frame member formed of a hollow portion with flange-sections extending lengthwise thereof, and a journal-head formed of a hollow body having flanges along one side and containing an opening for a shaft, the hollow body of said journal-head surrounding the hollow portion of said frame-member and the flanges of said head overlapping said flange-sections, and means connecting said parts together at said flanges and flange-sections.

11. In a frame adapted for pivotal support, the combination of a cross-member and a device connected therewith for attachment to means for rocking said frame, said device comprising a plate presenting oppositely-extending portions, with an intermediate off-set portion at which said plate straddles said cross-member, and a plate lo-

130

cated at the opposite side of said cross-member and connected with said first-named plate and having an off-set section at which said second-named plate straddles said cross-member.

12. In a frame adapted for pivotal support, the combination of a frame-member, a cross-member connected therewith, and a device connected with said cross-member for attachment to means for rocking said frame, said device comprising a plate presenting oppositely extending portions with an intermediate off-set portion at which said plate straddles said cross-member, and a plate located at the opposite side of said cross-member and connected with said first-named plate and having an off-set section at which said second-named plate straddles said cross-member, the edge-portions of said plates adjacent said frame-member conformingly fitting the side walls of the latter.

13. A frame-member formed from an integral body of metal into a hollow body-portion with flange-sections extending lengthwise thereof and having portions of the flange-sections cut away to permit the frame-member to be bent into curved condition.

14. A frame structure comprising a frame-member formed of a hollow body-portion with flange-sections extending lengthwise thereof, said flange-sections being relatively deep at certain portions only thereof, and cross-members connected with said flange-sections at the relatively deep portions thereof.

15. A frame-structure comprising a frame-member formed of a hollow body-portion with flange-sections extending lengthwise

thereof, said flange-sections being relatively deep at certain portions only thereof and entirely cut away at other portions thereof, and cross-members connected with said flange-sections at relatively deep portions thereof.

16. A frame-member formed from an integral body of metal into a hollow body-portion with flange-sections extending lengthwise thereof, portions of the body-portion being unflanged to permit the frame-member to be bent into curved condition. 45 50

17. A frame-member formed from an integral body of metal into a hollow body-portion with flange-sections extending lengthwise thereof, portions of the body-portion being unflanged to permit the frame-member to be bent into curved condition, the metal at the unflanged portions thereof being united. 55

18. A frame-member formed from an integral body of metal into a hollow body-portion with flange-sections extending lengthwise thereof, portions of the body-portion being unflanged to permit the frame-member to be bent into curved condition, and means fastening together the opposed edges of the frame-member. 60 65

19. A frame-member formed from an integral body of metal into a hollow body-portion with flange-sections extending lengthwise thereof, portions of the body-portion being unflanged to permit the frame-member to be bent into curved condition, and means for fastening the opposed edges of the frame-member engaging the flange-sections of said member. 70

DANIEL J. MURNANE.
